United States Patent Office.

DESIGN FOR AN ORNAMENTAL PICTURE FOR ANIMAL STUDIES.

CHARLES A. FOSTER, OF NORTH PROVIDENCE, RHODE ISLAND.

Design No. 2,514, dated December 4, 1866.

SPECIFICATION.

TO ALL WHOM IT MAY CONCERN:

Be it known that I, CHARLES A. FOSTER, of North Providence, in the county of Providence, and State of Rhode Island, have originated and produced a new Design for an Ornamental Picture of Animal Studies, of a "Gray String Team," (of horses,) of which the following is a full, clear, and exact description, reference being had to the accompanying specimens, making part of this specification.

In the said specimen picture there are six powerful gray horses, harnessed tandem or singly in a string, one before the other, and to a heavy team wagon, such as is used for transporting merchandise in considerable quantities from place to place. The said "team" is represented as having just halted on the road, with the tug chains or traces slackened, and the several horses in the attitudes which are peculiar to or indicative of their respective dispositions or temperament, and otherwise calculated to exhibit their symmetry of form and muscular development as specimens of draught horses.

What I claim as my invention, and desire to secure by Letters Patent, is—

The design for an ornamental picture of animal studies, of the "gray string team," as set forth and shown.

CHAS. A. FOSTER.
